UNITED STATES PATENT OFFICE.

PHILIP SAMUEL SPILLER, OF AUSTIN, TEXAS, ASSIGNOR OF ONE-HALF TO
HORACE P. HALDEMAN, OF AUSTIN, TEXAS.

HEATING OR COOKING STOVE.

SPECIFICATION forming part of Letters Patent No. 721,756, dated March 3, 1903.

Application filed August 13, 1902. Serial No. 119,513. (No model.)

To all whom it may concern:

Be it known that I, PHILIP SAMUEL SPILLER, of Austin, in the county of Travis and State of Texas, have made certain new and useful Improvements in Heating or Cooking Stoves, of which the following is a specification.

My invention relates to heating-stoves; and the invention consists of special details of construction and combination of parts, all as will be hereinafter fully described and the novel features pointed out in the claim.

In order to enable others to make and use my invention, I will now proceed to describe it in detail, reference being had to the accompanying drawings, and the letters of reference thereon, which form a part of this specification, and in which—

Figure 1 is a perspective view, part broken away, showing my invention in connection with a heating-stove; and Figs. 2 and 3 are perspective views of cooking-stoves, illustrating my invention in connection therewith, the latter view showing a stove with a common water-tank in position adapted to be heated.

In carrying out my invention I construct the body of a heating or cooking stove with double walls A and B. The said walls are arranged to provide a space or passage C, enclosing the body of the stove. Within the passage C, I arrange a diaphragm or division-wall D, slightly modified.

In Fig. 1 the diaphragm D extends from a point E, where it is riveted or otherwise secured to the outer walls of the stove. The said point of connection of the diaphragm D should be just above the smoke or gas escape pipe F and then curved inwardly to about midway of the heat-passage C and then continue down said heat-passage and around therein to a point G, near the burner H, which latter will be referred to farther on. It is apparent that with a diaphragm or division-wall E arranged in the heat-passage, as just described, the said heat-passage is formed into two legs or passages I J, the former serving to check or retard flow of the heat, and thereby providing increased radiation, and the latter providing a return-passage from the point G of the division-wall D to the exit-pipe F. With a heating-stove constructed

in radiator form, as shown in Fig. 1, and having the exit-pipe F connected as indicated increased radiation of heat is not only had from the inner wall B, but with a return-passage J, extending from near the burner H, the stove is provided with a heating-surface covering practically its whole body portion. For providing heat I employ a burner adapted to burn crude petroleum-oil, (in the several figures indicated, respectively, H H' H'') The burner is arranged in the passage C at the far side of the stove from the exit-pipe, and directly under the burner the passage C is closed by a trough K, from which latter extends a tube L, leading down through the floor to a suitably-located catch-basin or into the ground, as may be desired. The trough K is designed in addition to close the passage C at this point to catch escaping oil when lighting the burner or any dripping that may result from not completely closing the valve M in the feed-pipe N, which latter are only shown in Fig. 2 of the drawings.

O' O'' indicate draft-openings, and P P' show doors in the side walls above the draft-openings. The said doors may be hinged, as shown in Fig. 1, or sliding, as shown in Fig. 2. In Fig. 2 the exit-pipe F' is arranged to provide an outlet near the base of a cooking-stove.

The arrangement of the division-wall D in Figs. 2 and 3 is substantially the same; but in Fig. 3 the passage J ends into a passage R, extending up and over a common water-tank S to the exit-pipe F''.

It is obvious that my invention may be adapted, without departing from the spirit thereof, to any heating or cooking stove employing a grate should such stove have double walls adapted to form a heating-space similar to the space C shown in the several figures of my drawings.

Having thus fully described my invention, what I claim as new, and desire to secure by Letters Patent, is—

A heating-stove employing a substantially O-shaped open center body portion adapted to be supported in upright vertical position, the said body portion having an inner continuous heat-passage, a division-wall in the heat-passage extending from a point against the inner outer side wall of the body portion,

bove the smoke-outlet, and down the heat-
passage to a point near the far side of the
stove, providing a closed return-passage from
the said far side of the stove to the smoke-
outlet, a trough closing the heat-passage at
the far side of the stove from the smoke-out-
let, a burner in the heat-passage just above

the said trough, and a draft-opening in the
side wall of the body portion near the burner
substantially as described.

PHILIP SAMUEL SPILLER.
